UNITED STATES PATENT OFFICE.

WILLIAM C. HAPPE, OF DAVENPORT, IOWA.

SAW-COVER.

SPECIFICATION forming part of Letters Patent No. 757,740, dated April 19, 1904.

Application filed December 30, 1903. Serial No. 187,160. (No model.)

To all whom it may concern:

Be it known that I, WILLIAM C. HAPPE, a citizen of the United States, residing at Davenport, in the county of Scott, State of Iowa, 5 have invented certain new and useful Improvements in Saw-Covers; and I do hereby declare the following to be a full, clear, and exact description of the invention, such as will enable others skilled in the art to which it appertains 10 to make and use the same.

This invention relates to covers, and more particularly to those designed for the reception of tools to protect them from moisture, and has for its object to provide a device of 15 this nature which will be simple of construction and cheap of manufacture and will be especially designed to receive a saw, provision being made to prevent the teeth of the implement from injuring the fabric of which the 20 casing is made.

In the drawings forming a portion of this specification, and in which like numerals of reference indicate similar parts in the several views, Figure 1 is a side elevation of the casing 25 containing a saw. Fig. 2 is a longitudinal section of a portion of the casing, showing the position occupied by the saw therein. Fig. 3 is a section on line 3 3 of Fig. 1.

Referring now to the drawings, the present 30 invention comprises a casing 5, of canvas or similar material, which is formed from a single piece doubled and sewed along its free edges 6 and 7 and across its lesser end 8, its larger end 9 being left open for the reception 35 of a saw, it being understood that the casing has the general form of the implement.

To prevent the teeth of the saw from cutting the casing as it is placed therein and drawn therefrom, a strip 10 of wood or other 40 fibrous substance is provided and has a slot 11 opening longitudinally through one of its edges. This strip is disposed within the casing at the joint formed by the union of the edges 6 and 7 of the fabric, with its slotted 45 edge directed toward the interior of the casing, and to hold the strip in such position, as well as to strengthen the casing, a metallic binding-strip 12 is provided, which consists of a single piece bent upon itself longitudinally and having its edges 13 and 14 turned

inwardly toward each other. The sides of this strip are slightly wider than the strip 10, so that when the binding-strip is engaged with the edges 6 and 7 its inwardly-turned edges 13 and 14 lie above the strip 10, as shown. This 55 arrangement, by reason of the fact that the fabric and the two strips are wedged tightly together, holds the several parts of the device against accidental separation without the use of rivets or other fastening means, though 60 permitting of removal of the strip 10 when desired.

When the saw is placed in the casing, its toothed edge is engaged with the slot 11, and it is pressed downwardly therethrough, the 65 natural resiliency of the wood preventing the casing from accidentally falling from the saw.

At the open end 9 of the casing there may be disposed a suitable catch, which may be of the resilient head-and-socket type, one member 70 of which is attached to the casing at either side of the opening, and the members of this catch may be engaged one with another through the handle of the saw to hold the casing together.

In practice modifications of the specific construction shown may be made, and any suitable materials and proportions may be used for the various parts without departing from the spirit of the invention.

What is claimed is—

1. A covering for saws, comprising a casing, a strip of fibrous material disposed longitudinally within the casing at one edge thereof, and means for holding the strip within the 85 casing.

2. A covering for edged tools, comprising a casing of fabric, a strip of wood disposed within the casing for engagement of the edge of the tool, and a metallic binding-strip comprising spaced sides having inwardly-directed edges engaged with the edge of the casing, the wooden strip and a portion of the casing lying 90 between the spaced sides.

3. A covering for saws, comprising a casing, 95 a protection-strip disposed within the casing for engagement of the toothed edge of the saw, and means for holding the strip removably within the casing.

4. A covering for saws, comprising a casing 100

- of fabric having a protection-strip disposed longitudinally therein and in one edge thereof for engagement by the toothed edge of the saw, and a stiffening and binding strip engaged 5 with the edge of the casing exteriorly thereof, said strip having spaced arms embracing the protection-strip to hold the latter removably within the casing.
5. A cover for saws, comprising a casing of 10 fabric, a protection-strip disposed longitudinally therewithin and at one edge thereof for engagement by the toothed edge of the saw, and a metallic stiffening and binding strip comprising spaced sides directed toward each 15 other at their edges, said binding-strip being

engaged with the edge of the casing and lying with its spaced sides embracing the protection-strip and with its inwardly-directed edges lying therebeyond.

6. In a covering for saws, the combination 20 with a casing of fabric, of a protection-strip disposed within the casing for engagement by the toothed edge of the saw.

In testimony whereof I affix my signature in presence of two witnesses.

WILLIAM C. HAPPE.
